UNITED STATES PATENT OFFICE

JOHN EKERN OTT, OF CHICAGO, ILLINOIS, AND WILLIAM E. CLOSE, OF PHILADELPHIA, PENNSYLVANIA, ASSIGNORS TO ACME STEEL COMPANY, OF CHICAGO, ILLINOIS, A CORPORATION OF ILLINOIS

PAPER ROLL AND GUARD THEREFOR

Application filed July 17, 1929. Serial No. 378,872.

This invention relates to improvements in paper rolls and guards therefor and its purpose is to provide improved means for protecting the peripheral edges of paper rolls against injury. It is common practice to ship paper in large cylindrical rolls formed by winding a long strip of paper about the axis of the roll and the rolls thus formed are commonly protected by wrappings formed of heavy paper or other flexible coverings. It frequently happens that the edges of these paper rolls are cut or have indentations formed therein during shipment with the result that a large number of superimposed layers of paper at the outer portion of the roll are damaged. These damaged layers of paper cannot be used by the consumer and result in a considerable loss, particularly in the shipment of the better grades of paper. The principal object of the present invention is to provide a metallic guard adapted to extend around each peripheral edge of a roll of paper to prevent injury thereto during storage or shipment. A further object of the invention is to provide an improved metallic guard having novel means for securing the ends thereof together when the guard has been applied to the paper roll. Still another object of the invention is to provide an improved guard for paper rolls comprising a pair of projecting tongues adapted to be overlapped and to be engaged by a stretching device preliminary to the application thereto of a sealing or other fastening means by which the overlapping ends of the guard are secured together. Other objects relate to various features of construction and arrangement which will appear more fully hereinafter.

The nature of the invention will be understood from the following specification taken with the accompanying drawings, in which one embodiment is illustrated. In the drawings,

Fig. 1 shows an end elevation of an annular metal band or guard providing the features of the present invention and adapted for application to the edge of the paper roll;

Fig. 2 shows an enlarged plan view of the complementary ends of the band illustrated

in Fig. 1 when they have been displaced laterally from each other;

Fig. 3 shows a perspective view of a portion of a paper roll having the improved guard of the present invention applied to each annular edge thereof and illustrating a stretching device and a sealing device applied to the overlapping tongues at one end of one of the bands;

Fig. 4 shows a transverse section through the overlapping tongues carried by the ends of the bands with a channel-shaped sealing blank applied thereto preliminary to the operation of a sealing device for securing the overlapping ends of the band together;

Fig. 5 shows an end elevation of the paper roll after the metal band or guard has been applied thereto and the ends thereof secured together by a metal seal;

Fig. 6 is an enlarged plan view of the band illustrated in Fig. 4, showing the joint made by the metal seal at the overlapping ends thereof, and

Fig. 7 shows a side elevation of the paper roll illustrated in Fig. 4, with the metal guard applied to both ends of the roll.

The improved guard of the present invention comprises a curved band 10 comprising a substantially cylindrical body portion 10^a formed of sheet metal or the like and having an inwardly extending transversely corrugated flange formed integrally therewith. This band may be formed from a strip of sheet steel by bending one edge thereof transversely to form a flange and then providing the flange with a continuous series of transverse corrugations or the portion of the band which forms the flange may be corrugated prior to bending it inwardly. In the process of forming the band, it is passed through rolls to bend it into the annular form shown in Fig. 1 and the end portions of the band are arranged to overlap. The curvature of the band is such that its normal diameter is substantially the same as that of the roll of paper to which the band is to be applied with some allowance for contracting the band into tight engagement with the peripheral edge surface of the roll. The body portion 10^a

of the band is provided at one end with a 100

longitudinal slit 10^e forming a tongue 10^d which is of lesser width than the body portion 10^a and which extends for a considerable distance from the end of the band. The 5 corrugated flange 10^b preferably terminates adjacent to the end of the tongue 10^d. At the other end of the band 10, the corrugated flange 10^b and a portion of the body portion 10^a are cut away to leave a projecting tongue 10^e which is of the same width as the tongue 10^d and of at least equal length.

The band or guard thus formed is adapted to be applied to either peripheral edge of a roll 11 formed of a number of spiral convolutions of paper wrapped closely upon each other to form a cylindrical roll having a diameter substantially the same as, or preferably slightly greater than, the normal diameter of the guard 10, as illustrated in 15 Fig. 1. The roll of paper has the guard 10 applied to each annular edge surface thereof with the body portion 10^a of each guard surrounding and contacting with the cylindrical surface 11^a of the roll and with the corrugated flange 10^b extending inwardly and contacting with a radial surface 11^b formed by the superimposed edges of the layers of paper. When the band 10 has been applied to the roll 11, the tongue 10^d underlies the 20 tongue 10^e and the ends of the flange 10^b may preferably overlap. A sealing device 12 is then applied to the overlapping tongues 10^d and 10^e and is operated to effect relative movement of these tongues in a direction 25 adapted to tighten the band or guard around the roll. The stretching device 12 illustrated in Fig. 3 is of the form described and claimed in the co-pending application of Messrs. Chester M. MacChesney, Ralph H. 30 Norton and John Ekern Ott, Serial No. 276,659, filed May 10, 1928, and it comprises a housing 13 having a handle 14 and a base plate 15, which underlies the end of the tongue 10^e. A gripping dog 16 engages the 35 upper side of the tongue 10^e to hold it on the base plate 15 against movement toward the left, as viewed in Fig. 3. A bar 17 is slidably mounted in the housing 13 and carried by a head 18 having a part underlying the 40 tongue 10^d, the free end of which extends in a direction opposite to that of the end of the tongue 10^e. A gripping dog 19 mounted on the head 18 engages the upper side of the tongue 10^d to prevent relative movement 45 thereof with respect to the head 18 toward the right, as viewed in Fig. 3. The bar 17 is provided with rack teeth 17^a and the housing 13 contains suitable operating mechanism 50 engaging the rack teeth and operated by a handle 20 so that when the handle 20 is moved upwardly toward the handle 14, the housing 13 and the head 18 are moved away 55 from each other, thereby effecting relative 60 movement of the tongues 10^d and 10^e with the

result that the guard or band 10 is tightened around the roll.

When the desired degree of tautness has been obtained in the band 10, the overlapping ends of the tongues 10^d and 10^e are held 70 in that condition by the stretching device 12, as illustrated in Fig. 3, and there is then applied to the overlapping tongues a suitable seal for securing them in fixed relation to each other. In Fig. 3 of the drawings, there is illustrated a sealing device 21 of the form described and claimed in the co-pending application of Messrs. Chester M. MacChesney and John Ekern Ott, Serial No. 149,307, filed November 19, 1926, comprising a pair of 80 handles 22 which have pivotal connections with a pair of side plates 23 and which operate sealing heads 24 provided with suitable dies for operating upon a channel-shaped seal whereby the walls of the seal are bent into 85 overlapping relation to the tongues and the edges of the seal and the tongues are then bent and partially sheared to provide the form of completed seal described and claimed in the United States patent of Ralph H. Norton No. 1,260,106, dated March 19, 1918. In Fig. 4, the channel-shaped seal 25 is shown in position engaging the overlapping tongues 10^d and 10^e and having the flanges 25^a of the seal extending downwardly at the sides of the 90 tongues. Upon applying the sealing device 21 to the sealing blank shown in Fig. 4, and moving the handles 22 thereof inwardly, the walls or sides 25^a of the seal are bent inwardly 95 over the ends of the tongues and portions of the edges of the seal and of the tongues are then bent and partially sheared as shown at 100 26 in Fig. 6. This bending and partial shearing of the seal and the tongues secures the 105 tongues in fixed relation to each other, thus holding the guard or band 10 in tight frictional engagement with the peripheral surface of the paper roll so that it cannot readily be removed therefrom. After the seal 25 has 110 been applied to the tongues to secure them together, the projecting end of the tongue 10^e is preferably broken off by bending it back and forth or by cutting it, as shown at 27 in Fig. 6. By means of this invention, a guard or band 10 may be applied to both ends of the 115 cylindrical roll of paper, as shown in Fig. 7, so that the edges of the paper sheets are protected and the band is held in place entirely by its tight frictional engagement with the outer layer of paper so that no fastening 120 means are necessary and injury to the paper is thereby avoided. After the guards or bands 10 have been applied to the paper roll, the usual outer wrappings of cloth or heavy paper 125 may be applied around the outer surfaces of the roll and of the guards.

Although one form of the invention has been shown and described by way of illustration, it will be understood that it may be 130

constructed in various other embodiments within the scope of the appended claims.

I claim:

1. The combination with a paper roll, of an annular metallic band engaging the peripheral surface of the roll at the end thereof and having an annular flange extending inwardly adjacent the end surface of the roll, said band being provided at one end with a longitudinal slit forming a tongue and having at the other end a projecting tongue similar to said first named tongue, said tongues being superimposed upon each other when said band is applied to the roll, and means engaging said tongues for securing the ends of said band together.
2. The combination with a paper roll, of an annular metallic band engaging the peripheral surface of the roll at the end thereof and having an annular flange extending inwardly adjacent the end surface of the roll, said band being provided at one end with a longitudinal slit forming a tongue and having at the other end a projecting tongue similar to said first named tongue, said tongues being superimposed upon each other when said band is applied to the roll, and a sealing device enclosing said tongues and having parts forming an interlocking engagement therewith for securing the ends of said band together.
3. The combination with a paper roll, of a flat band forming an annular guard extending around said roll at its end and having a transversely extending flange projecting inwardly adjacent the end of said roll, said band being provided at one end with a projecting tongue and at the other end with a tongue of narrower dimensions than said band which projects therefrom at a point removed from the extremity of said band, whereby said tongues may be overlapped and the ends of said flange may be overlapped on the end of said roll, and means for securing said overlapping tongues together.
4. The combination with a paper roll, of a flat metal band forming an annular guard extending around said roll at its end and having a transversely extending transversely corrugated flange projecting inwardly adjacent the end of said roll, said band being provided at its opposite ends with projecting tongues of narrower width than said band whereby said tongues may be overlapped and secured together, one of said tongues being united with the body of said band at a point displaced from the end thereof whereby the body portions of said band and of said flange are overlapped independently of the overlapping of said tongues.
